[57] CLAIM

The ornamental design for a supporting bracket for a flower pot or similar article, as shown and described.

DESCRIPTION

FIG. 1 is an exploded perspective view of a supporting bracket for a flower pot or similar article showing my new design;

FIG. 2 is a side elevational view thereof;

FIG. 3 is a top plan view thereof;

FIG. 4 is a perspective view thereof;
FIG. 5 is a perspective view of a second embodiment of the design of FIG. 1;

FIG. 6 is an exploded perspective view of FIG. 5;

FIG. 7 is a side elevational view of FIG. 5; and

FIG. 8 is a top plan view of FIG. 5.

FIG. 4

FIG. 5

FIG. 6
